FIBREBOARD FORK LIFT CONTAINERS

Marion F. Adams, Indianapolis, Ind., assignor to Inland Container Corporation, Indianapolis, Ind., a corporation

Filed Jan. 31, 1955, Ser. No. 484,911

2 Claims. (Cl. 229—14)

This invention relates to a fibreboard container adaptable for shipment of large and somewhat heavy products, of a character suitably constructed to permit of the convenient handling and transporting by the usual industrial power lift trucks.

It is common practice in the industry to employ fork lift trucks wherein the forks extend into or are engaged under a pallet on which containers or articles are supported for the purpose of lifting, transporting and stacking. It has also been the practice in connection with open frame wooden crates to provide a suitable fork lift therefor wherein the forks will extend under the top framework of the crate for lifting it from the top instead of through the medium of a pallet at the bottom.

It has also been proposed in respect to heavy fibreboard cartons or containers to provide in the bottom thereof reinforced channels along the bottom of the container for lifting it from the bottom with all the weight of the contents carried by reinforced channels connected with the bottom of the container, and whereby said channels are further designed to admit and guide the forks free of the contents. In other words, such fibreboard containers having solid walls are provided with a bottom portion which rather serves as a built-in false bottom pallet structure.

It is the purpose of this invention to provide a fibreboard container of the simplified slotted box type for packaging heavy articles which may be fork lifted from the top so that no false bottom or reinforced channel arrangement is necessary. By reason of this construction such a container is not only of simplified form, but permits entry of the forks above the contents so as not to interfere therewith, and directly under a reinforced top structure from which the walls and bottom are suspended. By reason thereof, as more particularly herein-after described, there is little departure from the simple inexpensive slotted box type of container, resulting in economical packaging for power handling.

The full nature of the invention will be understood from the accompanying drawings and the following description and claims:

Fig. 1 is a perspective view of a fibreboard container embodying the invention, and with portions thereof broken away.

Fig. 2 is a section taken on the line 2—2 of Fig. 1, showing the position of a lifting and transporting fork in engaging position therewith.

Fig. 3 is a perspective view of the top of the container with the top panel partially removed.

Fig. 4 is a section through a corner portion of the container similar to Fig. 2, showing a modified form of reinforcing structure.

Fig. 5 is the same as Fig. 4, showing a second modified form.

Fig. 6 is a perspective view of a container showing a further modified form.

Figs. 7 and 8 are views similar to Fig. 2 showing the modified form of container illustrated in Fig. 6.

2

In the drawings there is shown as one example of the invention, a fibreboard container of the slotted box type for packaging heavy articles including fibreboard side walls 10 and 11 having a reinforcing top panel 12, and the usual bottom structure (not shown) of said containers. One of the side walls 10 is provided with a closure flap 13 overlying the adjacent edge of the side wall 11 and secured thereto in any suitable manner such as by the staples 14. Interiorly of the container there are provided corner reinforcing posts of fibreboard, as shown at 15, and side wall protective liners 16 which may be spaced inwardly thereof. The top panel structure 12 is preferably formed of a wooden reinforced core frame 17 over which fibreboard plies 18 and 19 are secured. Said top panel structure is seated over the ends of the corner posts 15 and the upper edges of the liners 16. The top edges of the side walls 10 and 11 are folded over to provide a gripping flange 20 extending over the upper edge portion of the top structure and secured thereto in any suitable manner, such as by glue or staples.

One or more adjacent side panels 10, 11 are provided along their upper edges and directly under the top structure with a plurality of spaced fork receiving openings 21, such as to receive therethrough the tines 22 of a lifting fork, as shown in Fig. 2. Said openings are cut from the side panels to leave a closure flap 23 hinged thereto.

In the above described structure, as shown in Figs. 1, 2 and 3, the lifting fork tines 22 may be readily inserted through the openings 21 pushing the flaps 23 inwardly to engage directly under the reinforced panel 12. The container may thus be lifted by the fork for transporting and stacking, sustaining the weight of the contents through the depending fibreboard side walls 10, 11.

Fig. 4 is illustrative of a similar structure having side walls 110, the upper edges of which are folded over and about a rigid reinforcing frame 117. A top panel 112 extends along the reinforcing frame 117, having downturned flanges 120 extending about the frame and having a lip 118 extending upwardly between the frame and the side wall to lock the frame in position about the top portions of the side walls. A steel strap or wire indicated at 119 is tightly secured about the flanges 120 for securely locking them, together with the reinforcing frame 117, to the side walls. One or more side walls is provided with the tine receiving openings 121, as above described, whereby the lifting fork may be inserted into the container immediately below and in lifting engagement with the reinforcing frame 117.

50 In the modified form shown in Fig. 5, the side walls 210 have turned over flanges 217 interlocking with an upturned flange 218 extending from the downturned flange portion 220 of the top panel structure 212. The tine receiving openings 221 formed in the walls 210 are immediately below the interlocking of the top cover for lifting engagement therewith. The top structure 212 is further reinforced by a steel band, or other securing means 219 extending about the downturned flange 220 to secure it in interlocking engagement with the side walls.

55 Thus, in the modified form of Fig. 4, the top panel is rendered rigid and reinforced by the frame 117, and in Fig. 5 the top structure is rendered rigid and reinforced by the interlocking flanges 217, 218, and wherein both are held in their rigid reinforced condition by the surrounding bands, or other securing means 119 and 219.

In the modified form of the invention as shown in Figs. 6, 7 and 8, the rigid reinforced top structure is located slightly below the top of the container, there being illustrated a container having side walls 310 and 311 with a top structure indicated generally at 312 which includes overlying closure flaps 319 hinged to the

side wall portion 320. The side wall portion 320 comprises in this modification the equivalent of the reinforced top structure of Fig. 1, and has its lower part cut out from the fork tine openings 321 of the side wall 310. Said cut out portion provides an inwardly disposed upturned flap 318 which embraces the reinforcing frame structure 319 and is stapled or otherwise secured thereto, as indicated at 316.

In Fig. 8 a very similar arrangement is shown, but wherein what may be termed the top structure 420 terminates in an inwardly disposed downturned flap 418 which is cut out from the adjacent opening 421 in the side wall 410. Said flap 418 embraces and locks in place the rigid reinforcing frame 317 to which it is secured by means indicated at 316. Thus, the tine 22 may be inserted through the opening 421 to engage directly under the rigid reinforced top structure including the frame 317.

From the foregoing it will be observed that the fibreboard container of the slotted box type for packaging heavy articles may embody one of the several modified arrangements of fibreboard side walls 10, 11, 110, 210, 310 and 410, and each of which containers is provided with any suitable bottom structure carried by the lower portions of said side walls. In each modification there is provided a rigid reinforced top structure secured to the upper portions of said side walls, said reinforced top structure being of the type shown in Figs. 1, 4 and 5 or as shown in Figs. 6, 7 and 8. Directly under the reinforced top structure, as by the wooden frame members 17, 117 and 317 on the one hand, or the folded interlocking fibreboard arrangement, as shown at 217 and 218, there are provided tine receiving openings for engagement therewith by the lifting fork, and wherein the lifting fork will directly engage the reinforced portions of said top structure for lifting the entire container and article therein through the tensile strength of the several fibreboard side walls.

The invention claimed is:

1. A fibreboard packing case of the slotted box type for packaging very heavy articles of merchandise and movable from one point to another with the aid of a fork lift truck, said case having single thickness side walls and a bottom wall of fibreboard, a relatively rigid top closure structure generally conforming in size and shape to the cross section of said case and fitted within an end thereof, inwardly bent extensions hinged to the side walls extending over said closure structure means to se-

cure said extensions against outward movement relative to said closure structure, and a series of spaced openings in at least one of said side walls to admit the tines of a lift fork therethrough for lifting engagement with said closure structure, the lower edge of said closure structure being disposed in substantially the same plane with the upper edges of said openings, whereby the lifting forces exerted by said tines will be distributed through said closure structure to and throughout the walls of the case.

2. A fibreboard packing case of the slotted box type for packaging very heavy articles of merchandise and movable from one point to another with the aid of a fork lift truck, said case having single thickness side walls and a bottom wall formed of fibreboard, a relatively rigid top closure structure generally conforming in size and shape to the cross section of said case and fitted within an end thereof, inwardly bent extensions hinged to the side walls extending over said closure structure, means to secure said extensions against outward movement relative to said closure structure, a plurality of corner reinforcing posts disposed within said case upon which said closure structure is seated, and a series of spaced openings in at least one of said side walls to admit the tines of a lift fork therethrough for lifting engagement with said closure structure, the lower edge of said closure structure being disposed in substantially the same plane with the upper edges of said openings, whereby the lifting forces exerted by said tines will be distributed through said closure structure to and throughout the walls of the case.
